(57) **CLAIM**

The ornamental design for a golf hitting mat, as shown and described.

DESCRIPTION

FIG. 1 is a perspective view of first embodiment of a golf hitting mat showing my new design;
FIG. 2 is a front view thereof;
FIG. 3 is a back view thereof;
FIG. 4 is a left side view thereof;
FIG. 5 is a right side view thereof;
FIG. 6 is a top plan view thereof;
FIG. 7 is a bottom plan view thereof;
FIG. 8 is a perspective view of second embodiment of a golf hitting mat showing my new design;
FIG. 9 is a front view thereof;
FIG. 10 is a back view thereof;
FIG. 11 is a left side view thereof;
FIG. 12 is a right side view thereof;
FIG. 13 is a top plan view thereof; and,
FIG. 14 is a bottom plan view thereof.

1 Claim, 14 Drawing Sheets
